COMBINED ALTAR AND PRAYER BENCH

Madeleine M. Shaw, Box 16, R.R. 1, Islington,
Ontario, Canada

Filed May 1, 1961, Ser. No. 64,976

Term of patent 14 years

(Cl. D29—23)

FIG. 1

FIG. 1 is a perspective view of a combined altar and prayer bench showing my new design; and

FIG. 2 is a perspective view of the side opposite that of FIG. 1 as it appears with the table top leaves folded and the kneeling stools pulled out for use.

I claim:

The ornamental design for a combined altar and prayer bench, substantially as shown.
